OIL BURNER

Robert R. Witherell, Bloomington, Ill., assignor
to Eureka Williams Corporation, Bloomington,
Ill., a corporation of Michigan

Application October 11, 1949, Serial No. 120,801

9 Claims. (Cl. 158—76)

1

This invention relates to oil burners and has particular reference to certain new and useful improvements which relate to oil burners of the low pressure type wherein oil and air are supplied under a relatively low pressure to an air mixing nozzle which discharges the mixture into a secondary air stream. While burners of the low pressure type have been manufactured and sold for a considerable period of time, they have in general been relatively expensive. This invention has particular reference to a construction for a burner of this type which is of relatively low capacity and which may be manufactured at a lower cost than burners of this type which have been heretofore available.

An oil burner embodying the invention comprises in general a tubular casing, one end of which is adapted to be arranged in communication with a combustion chamber for discharging a combustible mixture of oil and air into such combustion chamber. The other end of the casing is provided with an air inlet opening for admitting air thereto, and within the casing there are arranged an electric motor, a fan, an air pump, an oil supply pump, an oil metering pump, an oil and air mixing nozzle, the electrodes of an ignition system for igniting the mixture, and suitable valves and other appurtenances forming a part of the operative mechanism of the burner, the parts named being arranged in a line within the casing and the casing forming a housing as well as a conduit through which secondary air is supplied past the nozzle to the combustion chamber.

A principal object of the invention is to provide a new and improved construction for oil burners.

Another object of the invention is to provide a novel and improved fuel and air supplying arrangement for oil burners.

Another object of the invention is to provide an efficient, low-cost, low capacity, high quality, power-operated oil burner.

Other and further objects of the invention will be apparent from the following description and claims and will be understood by reference to the accompanying drawings, of which there are three sheets, which by way of illustration show a preferred embodiment and the principles thereof and what I now consider to be the best mode in which I have contemplated applying those principles. Other embodiments of the invention embodying the same or equivalent principles may be used and structural changes may be made as desired by those skilled in the art

2

without departing from the present invention and the purview of the appended claims.

In the drawings:

Fig. 1 is a longitudinal sectional view of an oil burner embodying the invention;

Fig. 2 is an enlarged fragmentary sectional view of part of the structure shown in Fig. 1;

Fig. 3 is a sectional view of the air pump taken along the line 3—3 of Fig. 1;

Fig. 4 is a sectional view of the gear or oil supply pump taken along the line 4—4 of Fig. 1;

Fig. 5 is a sectional view of a pressure regulating valve taken along the line 5—5 of Fig. 1;

Fig. 6 is a sectional view of the metering pump taken along the line 6—6 of Fig. 1; and

Fig. 7 is a sectional view through the oil and air mixing nozzle taken along the line 7—7 of Fig. 1.

As shown in Fig. 1, an oil burner embodying the invention comprises in general a tubular casing 10 having a nozzle or opening 12 in communication with a combustion chamber and through which opening 12 a stream of air charged with atomized oil is discharged into the combustion chamber. Within the housing 10 there is arranged an air and oil pumping and mixing unit which comprises a fan 14, a motor 16, an air pump 20, an oil supply pump 18, a centrifugally responsive valve 21, an oil metering pump 22, a pressure-operated, normally closed valve 24, an oil and air mixing nozzle 26, and ignition electrodes 28.

The casing 30 of the motor is supported by a pair of resilient rings 32. The metal rims 34 of the rings 32 are supported in spaced relation to the interior of the casing 10 by a plurality of fins 36 which extend longitudinally of the casing 10 on the interior thereof, thereby providing an annular air conducting passage 38 between the motor casing 30 and the interior of the casing 10. The motor casing 30 may be provided with a plurality of integral heat dissipating fins 40 extending into the passage 38 to aid in dissipating the motor heat. The motor casing houses the usual field and armature and bearings for the shaft 42 which projects beyond the casing 30 and at one end thereof has the fan 14 secured thereto. The end of the casing 30 adjacent the fan is formed to provide a cavity 44 within which a speed responsive switch indicated generally at 46 is arranged.

The switch 46 is mounted on the shaft 42 between the fan 14 and the motor 16 and is of the type which is adapted to cut out the starting windings of the motor when the same ap-

proaches its normal running speed. The switch 46 is shown in its position with the starting windings cut out of the motor circuit. The centrifugal switch is of the type disclosed in the application of Kemper M. Hammell et al., Serial No. 676,885, filed June 15, 1946, now U. S. Patent No. 2,573,968, for "Centrifugal Switch."

The casing 10 is provided with an air inlet 48 opposite the center of the fan 14, and an air valve indicated generally at 50 is arranged ahead of the inlet 48 so that the air intake to the fan may be regulated. The valve 50 comprises two perforated discs 52 and 54 pivoted together by rivet 56 so that the perforations in the discs may be moved into or out of registry with each other in order to increase or decrease the supply of air to the fan 14.

The motor casing 30 is provided with a socket 58 accommodating a thermostatically operated safety switch 60 which is arranged to open the circuit of the motor 16 in the event of overheating thereof. This switch may be of the type disclosed in Samuel E. Vickers Patent No. 2,473,485, issued June 14, 1949, for "Thermal Overload Device," and needs to be manually reset. To this end a diaphragm 62 is incorporated in the casing 10 opposite the reset button 64 of the switch 60 so that if the switch opens, it may be reset after the motor has cooled down.

The motor shaft 42 also extends beyond the motor casing 30 in the other direction and is connected to the air pump 20, the oil supply pump 18, the centrifugally responsive valve 21, and the metering pump 22 for operating the same.

It should be noted in connection with Figs. 1 and 2 that the passages or ducts as shown are illustrated somewhat diagrammatically in order to illustrate the system and the fluid connections between the various parts of the oil burner, while in Figs. 3, 4, 5, 6 and 7 the sections 40 are of the burner as actually designed.

The right hand end of the motor casing 30 is formed by a frame having a cavity 68 exposed to the interior of the motor casing 30. The air pump 20 is disposed within this cavity 45 and comprises plates 70 and 72 with cylinder 74 secured therebetween, such plates and cylinder 74 defining the pump chamber 76 (Fig. 3). The air pump 20 is of the rotary sliding vane type and further includes a rotor 78 mounted and 50 keyed to the shaft 42 and having a series of radially extending slots in each of which a vane 80 is slidably arranged so that upon rotation of the rotor air will be drawn into the pump chamber 76 through the inlet 82 thereof, compressed, and discharged under the regulated pressure through the discharge 84. From the discharge 84 air is conducted through the passage or duct 86 to the nozzle 26.

The shaft 42 extends through an opening in 60 the rotor 78, and a pin 88 disposed in a hole through the shaft 42 and in a slot 90 in the rotor 78 keys the rotor 78 to the shaft 42 for rotation therewith. A seal 92 for the shaft 42 is disposed in a socket 94 formed in the pump plate 70. A flexible diaphragm 96 is clamped by the plate 72 to a wall or partition 98 of the frame 66, and the plates 70 and 72 and the cylinder 74 are clamped in the assembly as shown to the partition 98 by bolts 100, the ends of which are threaded secured in threaded openings in the partition 98.

The pump 20 is provided with a by-pass comprising ducts 102 and 104 between the discharge 84 and the inlet 82, and this by-pass is con- 75

trolled by a valve 106 which is adjustable so as to regulate the discharge pressure of the pump 20. The pump inlet 82 communicates with the cavity 68 which may be supplied with air through a series of ports 110 in the motor casing.

The partition 98, plate 72 and plate 112 co-operate to define a seal and bearing chamber 114. The bushing 116 of a self-aligning type of bearing is seated in a socket 118 formed on the plate 112, and a spring plate 120 seated against a shoulder in the chamber 114 forms a socket for the other end of the bushing 116 and confines the same against the seat provided by the socket 118. Shaft 42 is journaled in the bearing bushing 116 and projects therebeyond.

A running seal indicated generally at 122 is arranged between the partition 98 of the frame and the shaft 42 and includes the diaphragm 96, a coil spring 124, a bushing 126, a seal ring 128, a cup-shaped sealing ring 130, a ring 132 of resilient material, a washer 134, and a snap ring 136. The ring 132 of resilient material is arranged inside of the cup-shaped ring 130 and forms a seal between the ring 130 and the shaft 42. The ring 130 rotates with the shaft 42 and is held in position by the ring 132, the washer 134, and the snap ring 136 which is anchored in a groove in the shaft 42.

The seal ring 128 and an annular radially extending portion of the bushing 126 clamp the edges around the opening through the diaphragm 96 therebetween, and the other end of the bushing 126 is expanded over the seal ring 128 so as to anchor the two parts together. The surface of the seal ring 128 and the contacting surface of the sealing ring 130 cooperate to define a running seal about the shaft 42 so as to prevent the flow of oil from the chamber 114 into the air pump housing.

The shaft 42 beyond the bearing 116 is hollow and extends into the discharge chamber 140 for the oil supply pump 18. The plate 112 co-operates with a sleeve 142 and the plate 144 to define the discharge chamber 140 in which the oil supply pump 18, the centrifugally responsive valve 21, and the metering pump 22 are arranged. The plate 112 is seated in a cavity in the frame 66, and the sleeve 142 and the plates 144, 146, 148 and 112 are bolted in assembled relation as shown to the frame 66, preferably with gaskets between adjacent faces of the parts so as to form an effective seal between the portions of the ducts and passages which extend through such parts.

The oil supply pump (Figs. 2 and 4) may be of the gear type and comprises gears 150 and 152, the latter being keyed to the shaft 42 so as to rotate therewith. The gears are arranged in a pump chamber 154 provided with an inlet 156 and an outlet 158, the teeth of the gears being in mesh and the gear 150 being rotatable on a shaft 160. The pump chamber 154 is defined by a block 162, the plate 112 and a plate 164 suitably secured in assembled relation by bolts 166. The pump outlet 158 opens into the discharge chamber 140. The inlet of the pump 18 is supplied with oil from a suitable reservoir through duct or passage 168.

A filter assembly 170 is arranged between the pump 18 and the oil supply tank and is provided with an inlet port 172 to which the fuel line from the oil tank is connected and an outlet port 174 which is connected by a conduit to the oil supply tank to return excess oil thereto. Upon entering the filter unit 170 the oil flows through duct 176

and ports 178 and through filter 180 into chamber 182. From chamber 182 oil flows through duct 184 which is connected by a fuel line indicated diagrammatically at 186 to the duct 168 for supplying oil to the suction pump 18.

The filter unit 170 also includes a duct 188 which is connected by fuel line 190 to duct 192 which communicates with the seal and bearing chamber 114. Duct 192, line 190 and duct 188 form part of a by-pass for the suction pump 18. The duct 188 communicates past check valve 194 with duct 196 which is in communication with port 174 whereby the excess oil pumped by the pump 18 may be returned to the oil tank. If the threaded plug 198 which is shown obstructing the passage between the ducts 184 and 188 is removed and the port 174 is plugged, the by-passed oil will flow directly from the duct 188 into the duct 184. This is an alternative arrangement for the by-pass.

The pressure regulating valve 21 and the metering pump 22 are arranged in the discharge chamber 140. A rotor 200 is keyed on the hollow extension 202 of the shaft 42. The right hand face 204 of the rotor is a lapped face and seats and rotates against a similarly lapped face 206 formed on the plate 144. A ball 208 is seated in the end of the hollow portion 202 of the shaft and in a socket in the rotor 200. The seal spring 124 reacting through the seal and the shaft 42 and the ball 208 biases the rotor 200 against the face 206 on the plate 144.

The rotor 200 is provided with a diametrically extending bore 210, one end of which is closed by plug 212. The other end of the bore terminates in a reduced opening forming a port 214 between the discharge chamber 140 and the valve chamber 216 formed by the bore within the rotor 200. The valve chamber 216 is in communication with the interior of the hollow portion 202 of the shaft 42. A ball valve 218 is arranged in a cage 220 in the valve chamber 216. A pin 222 projecting from the plug 212 retains the ball 218 in its cage.

The hollow interior of shaft portion 202 communicates through cross duct 224 in the shaft 42 with the seal and bearing chamber 114. Thus the port 214, the valve chamber 216, the hollow portion of the shaft 202, the cross duct 224, the seal and bearing chamber 114, and the duct 192 form part of a by-pass between the discharge and inlet sides of the pump 18, and flow through this by-pass is controlled by the centrifugally responsive valve 21 which includes the rotor 200, the port 214, the valve member 218 and the seat for the valve 218 formed by the inner edge of the port 214. When the shaft 42 is not rotating, the ball valve member 218 is unseated so that the port 214 is open. However, rotation of the shaft 42 and of the rotor 200 will cause the valve member 218 under the influence of centrifugal force to move outwardly toward its seat to restrict or close the port 214.

The pump 22 includes cylinders 230 and 232 formed by a diametrically extending bore in the rotor 200, the bore being divided into the cylinders 230 and 232 by the plug 234 which is arranged at the center of the bore. A pin 236 is slidably arranged in the plug 234. A piston 238 is arranged in the cylinder 232 and a piston 240 is arranged in the cylinder 230. A ring 242 surrounds the rotor 200 and is eccentrically disposed with respect thereto. The outer ends of the pistons 240 and 238 bear against the inner periphery of the ring 242. The piston 240 in-

cludes a head 244 having a stem 246 and a separate plunger part 248, and a spring 250 confined between the part 248 and the head 244 biases the head 244 and the part 248 apart.

The head 244 reacting through the pin 236 biases the piston 238 toward the ring 242. In this way the outer ends of the pistons 238 and 240 will always bear against the inner periphery of the ring 242. As the ring 242 is disposed off-center relative to the rotor 200, it will be evident that upon rotation of the rotor the pistons 240 and 238 will move in and out in their respective cylinders, and when the piston 238 is arranged as shown in Figs. 2 and 6 the cylinder 232 will be in communication with the oil inlet port 250 which communicates through duct 252 with the discharge chamber 140. At the same time the cylinder 230 will be in communication with the discharge port 254 which communicates through duct 256 with the valve chamber 259. Thus, upon rotation of the rotor 200 the cylinders 230 and 232 will alternately be brought into registry with the oil supply port 250 and supplied with oil, and such cylinders also will be brought alternately into registry with the discharge port 254, and the pistons, due to the eccentric arrangement of the ring 242, will effect the discharge of oil from the cylinders through the discharge port 254 and duct 256 into the valve chamber 259.

The pressure operated, normally closed valve 24 comprises a flexible diaphragm 270 which is clamped between plates 144 and 146 and which separates valve chamber 260 from valve chamber 272. The diaphragm 270 has secured to it a valve body 274 which is slidable in a cylinder 276, the body 274 being provided with an annular groove in which an O-ring 278 is arranged and which forms a seal between the cylinder 276 and the valve body 274 so as to separate valve chamber 260 from valve chamber 259.

The valve body 274 is provided with a hollow valve stem 280 having ports 282 which in the position shown are in communication with the valve chamber 259, thereby providing for the flow of metered oil from the duct 256 through the ports 282, the hollow valve stem 280, and the pipe 284 into the nozzle 26.

The valve stem 280 is slidable in the bore 286. The valve stem 280 is made so as to have approximately .005 inch clearance in relation to the bore 286 and which clearance serves as a metering orifice to allow a small amount of oil to flow from the chamber 259 to the duct 286 which leads to the suction side of the air pump 20 for supplying lubricant to the pump 20. This lubricant supplied to the pump 20 not only lubricates the working parts thereof, but helps to form a seal around the blades and the rotor, and any excess lubricant supplied to the pump is delivered with the air supplied by the pump to the nozzle through the air duct 86.

A spring 290 is arranged to react against the diaphragm 270 so as to urge the valve body 274 toward its seat 292, thereby to close the valve 24. Oil under pressure supplied to the chamber 260 through the duct 294 from the discharge chamber 140 will act on the diaphragm 270 and open the valve 24. In the burner illustrated the centrifugal pressure regulating valve is constructed and arranged to maintain a pressure in the discharge chamber 140 of from 12 to 14 p. s. i. (pounds per square inch) during normal burner operation. This pressure, however, falls off very rapidly when the burner motor falls below the normal running speed of the motor, and when

the motor is at rest the pressure in the discharge chamber 140 is entirely dissipated. The valve 24 is set to open at a pressure of 7 p. s. i. applied to the diaphragm 270, and closes when this pressure drops to 5 p. s. i. This differential probably is caused by the drag of the O-ring 278. The pressure at which the valve 24 operates can, of course, be changed by varying the loading of the spring 290.

The valve chamber 272 communicates through duct 300 with the seal and bearing chamber 114. During operation of the pump 22 before the valve 24 opens, the pressure of the oil in the duct 256 will cause the face 204 of the rotor 200 to move slightly away from the face 206 of the plate 144, thereby permitting the oil discharged from the pump 22 to escape back to the discharge chamber 140. When the valve 24 opens, oil is supplied through the valve stem 280 and the bore 286 and the pipe 284 to oil ports 302 in the nozzle 26.

The oil ports 302 discharge jets of oil into the air passages 304 which are supplied with air from the pump 20 through the duct 86. The nozzle 26 is constructed and arranged to mix the oil and air and to discharge such mixture through the knife-edge orifice 306 into the stream of air which flows past the nozzle and out the opening 12. The nozzle 26 may be of the construction as disclosed and claimed in the application of Hubert J. Wiser, Sr., Serial No. 14,731, filed March 13, 1948, now U. S. Patent No. 2,568,878 for "Oil Burner Nozzle."

The valve 24 will shut off the flow of oil from the metering pump 22 to the nozzle 26 when the pressure in the chamber 260 is partially dissipated, which occurs immediately as soon as the shaft 42 and the rotor 200 fall below a predetermined speed of rotation. In other words, on deceleration of the rotor and the shaft 42 from the normal running speed thereof, the ball valve 218 will move to an unobstructing position relative to its seat on the port 214 as soon as the shaft 42 falls below, say for example, 75% of its normal running speed.

In the oil burner herein disclosed, the normal running speed of the motor and shaft is approximately 3450 R. P. M. The movement of the valve 218 to an unobstructing position relative to the port 214 will dissipate the pressure in the discharge chamber 140 and in the valve chamber 260 and permit the spring 290 to close the valve 24 by moving the same to its seated position.

The following table computed from the laws governing centrifugal force illustrates the corresponding operating pressures that can be generated at various angular speeds:

Percent of Angular Speed	Percent of Normal Hydraulic Pressure
0	0
10	1
20	4
30	9
40	16
50	25
60	36
70	49
80	64
90	81
100	100

In this instance, resistance to flow is created by directing the rotated mass of the ball valve 218 against the fluid stream flowing into the chamber 216 through the port 214 so as to gen-

erate hydraulic pressure in the chamber 140 as a function of the motor speed, the pressure generated being transmitted and directed against the actuating diaphragm 270 of the shutoff valve 24. Thus the shutoff valve is hydraulically actuated and is designed to be opened and closed in response to the changes in pressure developed in the chamber 140 by the pressure regulating valve 21. Thus, closing of the valve 24 will cut off the supply of oil from the metering pump 22 to the nozzle 26 as soon as the motor speed falls below some predetermined percentage of its normal running speed.

It should be noted that the motor, pumps and valves and fan form an elongated unit which is arranged in the casing 10 in spaced relation with the walls thereof and that such unit is mounted in the casing 10 which is adapted to be mounted directly on the wall of the combustion chamber around the opening through which the nozzle end of the burner projects into the combustion chamber.

While I have illustrated and described a preferred embodiment of my invention, it is understood that this is capable of modification, and I therefore do not wish to be limited to the precise details set forth, but desire to avail myself of such changes and alterations as fall within the purview of the following claims.

I claim:

1. In an oil burner, oil pumping means having an inlet and a discharge chamber arranged to receive oil discharged by said pumping means, a rotor in said chamber, said rotor having a valve chamber provided with a port which communicates with said discharge chamber, a valve seat within said valve chamber, a centrifugally responsive valve member movable in said valve chamber, upon rotation of said rotor, toward said valve seat to seat thereon and close said port, a communication between the interior of said valve chamber and said inlet, a fuel metering pump having its inlet communicating with said discharge chamber so as to be supplied with fuel therefrom, a motor driven shaft arranged for driving said fuel metering pump and said pumping means and rotor, said shaft being hollow and forming a part of said communication, an oil and air mixing nozzle, a fluid connection between said nozzle and the outlet of said fuel metering pump so as to supply fuel from said metering pump to said nozzle, means for supplying air to said nozzle, a pressure operated normally closed valve in said connection constructed and arranged to be opened by the liquid pressure in said discharge chamber, said port, valve chamber and communication forming a by-pass between said inlet and discharge chamber of said oil pumping means, said valve member when seated closing said by-pass, the movement of said valve member towards said seat under the influence of centrifugal force being resisted by the fluid flow through said port.

2. In an oil burner, fuel pumping means having an inlet and a discharge chamber arranged to receive fuel discharged by said pumping means, a rotor in said chamber, said rotor having a valve chamber provided with a port which communicates with said discharge chamber, a valve seat within said valve chamber, a centrifugally responsive valve member movable in said valve chamber, upon rotation of said rotor, toward said valve seat to seat thereon and close said port, a communication between the interior of said valve chamber and said inlet, a fuel metering pump having its inlet communi-

cating with said discharge chamber so as to be supplied with fuel therefrom, a motor driven shaft arranged for driving said fuel metering pump, said pumping means and rotor, said shaft being hollow and forming part of said communication, a fuel and air mixing nozzle constructed and arranged to mix fuel and air and to discharge a mixture of fuel and air, a fluid connection between said nozzle and the outlet of said fuel metering pump so as to supply fuel from said metering pump to said nozzle, means for supplying air to said nozzle for mixture with the fuel supplied thereto, a normally closed valve in said connection constructed and arranged to be opened when the pressure in said discharge chamber attains a predetermined amount, said metering pump including provisions for returning the oil discharged thereby to said discharge chamber when said valve is closed, said port, valve chamber and communication forming a bypass between the inlet and discharge chamber of said pumping means, said valve member when seated closing said by-pass, the movement of said valve member towards said seat under the influence of centrifugal force being resisted by the fluid flow through said port, and means for flowing a stream of secondary air past said nozzle and into which stream said mixture of fuel and air is discharged.

3. In an oil burner, oil pumping means having an inlet and an outlet, and a by-pass therebetween, a centrifugally responsive valve constructed and arranged to resist flow of oil through said by-pass during operation of said pumping means thereby to create a pressure differential between said inlet and outlet, a fuel metering pump having its inlet connected to the outlet of said pumping means so as to be supplied with oil therefrom, an oil and air mixing nozzle connected to said metering pump so as to be supplied with oil therefrom, a pressure operated normally closed valve in the connection between said nozzle and said metering pump, said pressure operated valve being constructed and arranged to be opened by the pressure differential between the inlet and outlet of said pumping means created by said centrifugally responsive valve, said pump, pumping means and centrifugally responsive valve being arranged to be actuated simultaneously, means driven with said pump and pumping means for supplying air to said nozzle for mixture with the oil supplied thereto, and means for supplying a stream of air past said nozzle into which said nozzle discharges a mixture of oil and air, said oil burner including a tubular casing having an air inlet at one end and an outlet at the other end at which said nozzle is disposed and from which other end said stream of air charged with said oil mixture flows, said pumping means, metering pump, centrifugally responsive valve, nozzle and air supplying means forming a unit and being arranged in line in said casing.

4. In an oil burner, oil pumping means having an inlet and a discharge chamber arranged to receive oil discharged by said pumping means, a rotor in said chamber, said rotor having a valve chamber provided with a port which communicates with such discharge chamber, a valve seat within said valve chamber, a centrifugally responsive valve member movable in said valve chamber upon rotation of said rotor toward said valve seat to seat thereon and close said port, a communication between the interior of said valve chamber and said inlet, a fuel metering pump in

and having its inlet communicating with said discharge chamber so as to be supplied with fuel therefrom, said rotor forming part of said fuel metering pump, a motor driven shaft for driving said fuel metering pump and said pumping means and rotor, said shaft being hollow and forming a part of said communication and being connected to said rotor, an oil and air mixing nozzle, a fluid connection between said nozzle and the outlet of said fuel metering pump so as to supply fuel from said metering pump to said nozzle, a pressure operated normally closed valve in said connection constructed and arranged to be opened when the liquid pressure in said discharge chamber reaches a predetermined amount, said port, valve chamber and communication forming a by-pass between said inlet and discharge chamber of said oil pumping means, said valve member when seated closing said by-pass, the movement of said valve member towards said seat under the influence of centrifugal force being resisted by the fluid flow through said port.

5. In an oil burner, fuel pumping means having an inlet and a discharge chamber arranged to receive fuel discharged by said pumping means, a rotor in said chamber, a centrifugally responsive valve carried by said rotor and actuated upon rotation thereof, a fluid communication between said discharge chamber and said inlet controlled by said valve, a fuel metering pump carried by said rotor and having its inlet communicating with said discharge chamber so as to be supplied with fuel therefrom, a motor driven shaft arranged for driving said fuel metering pump, said pumping means and rotor, said shaft being hollow and forming part of said communication, a fuel and air mixing nozzle constructed and arranged to mix fuel and air and to discharge a mixture of fuel and air, a fluid connection between said nozzle and the outlet of said fuel metering pump so as to supply fuel from said metering pump to said nozzle, air pump means driven by said shaft for supplying air to said nozzle for mixture with the fuel supplied thereto, a seal chamber surrounding said shaft and disposed between said air pump means and said fuel pumping means and forming part of said communication, a seal in said seal chamber about said shaft and preventing oil flow along said shaft to said air pumping means, a pressure operated normally closed valve in said connection constructed and arranged to be opened when the pressure in said discharge chamber attains a predetermined amount, said communication forming a by-pass between the inlet and discharge chamber of said pumping means, said centrifugally responsive valve when seated closing said by-pass, the movement of said centrifugally responsive valve towards its seat under the influence of centrifugal force being resisted by the fluid flow through said by-pass, and means for flowing a stream of secondary air past said nozzle and into which stream said mixture of fuel and air is discharged.

6. In an oil burner, oil pumping means having an inlet and an outlet, and a by-pass therebetween, a centrifugally responsive valve constructed and arranged to resist flow of oil through said by-pass during operation of said pumping means thereby to create a pressure differential between said inlet and outlet, a fuel metering pump having its inlet connected to the outlet of said pumping means so as to be supplied with oil therefrom, an oil and air mixing

nozzle connected to said metering pump so as to be supplied with oil therefrom, a normally closed valve in the connection between said nozzle and said metering pump constructed and arranged to be opened when the pressure differential between the inlet and outlet of said pumping means created by said centrifugally responsive valve attains a predetermined amount, said pump and pumping means and centrifugally responsive valve being arranged to be actuated simultaneously, means driven therewith for supplying air to said nozzle for mixture with the oil supplied thereto, and means for supplying a stream of air past said nozzle into which said nozzle discharges a mixture of oil and air, said oil burner including a tubular casing having an air inlet at one end and an outlet at the other end at which said nozzle is disposed and from which other end said stream of air charged with said oil mixture flows, said pumping means, metering pump, centrifugally responsive valve, nozzle and air supplying means forming a unit and being arranged in line in said casing.

7. An oil burner air and oil pumping unit comprising an electric motor having a shaft projecting from both ends thereof, a fan on one end of said shaft, an air pump, an oil supply pump, a centrifugally operated valve and an oil metering pump arranged in the order named and connected to the other end of said shaft so as to be driven thereby, a discharge chamber into which said oil supply pump discharges and in which said oil supply pump, said centrifugally operated valve and metering pump are disposed, a seal and bearing chamber about said shaft and between said air pump and oil supply pump, a seal in said chamber and disposed about said shaft, said seal chamber forming part of a by-pass between said discharge chamber and the intake of said oil supply pump,

said centrifugally operated valve being arranged in said by-pass and operable for controlling the flow of oil therethrough, the intake of said oil metering pump being in communication with said discharge chamber, an air and oil mixing nozzle connected to said air pump and oil metering pump so as to be supplied with air and oil, said nozzle being arranged at one end of said unit, and a pressure operated valve operatively disposed in the connection between said metering pump and nozzle and opened by a predetermined pressure in said discharge chamber.

8. An oil burner according to claim 7 wherein one end of said shaft is hollow and forms part of said by-pass.

9. An oil burner according to claim 7 wherein said metering pump includes provisions for bypassing oil discharged thereby to said discharge chamber when said pressure operated valve is closed.

ROBERT R. WITHERELL.
